STOPPER PULL

John Oftedahl, Antioch, Ill.

Application October 30, 1948, Serial No. 57,468

2 Claims. (Cl. 215—55)

1

This invention relates to an improvement in stopper pulls, that is to say, to an arrangement for facilitating the withdrawal of a cork (or like) stopper from the mouth of a bottle or the like.

Bottle stoppers made of cork are a most effective closure for bottles but they can be withdrawn only with great difficulty, and usually in such damaged condition that reuse value of the stopper is seriously impaired, especially when the stopper is initially pressed into the bottle so as to leave no projecting portion which may be effectively gripped. It is, of course, very generally desirable that withdrawal of the stopper from a bottle or the like be effected in such manner that the stopper may be reinserted after the required amount of material has been poured out of the bottle or otherwise withdrawn therefrom. Of course, for reuse, the stopper should be intact and uninjured incident to the withdrawal or prying of the stopper out of the bottle.

The principal object of the present invention is to provide an effective means whereby a stopper of cork or similar material may be easily withdrawn from the mouth of a bottle, even though the stopper is inserted into the bottle mouth to such an extent that the stopper cannot be directly gripped for withdrawal purposes. Another object of the invention is to provide a stopper pull of the character indicated which may be easily applied to stoppers of cork and similar materials, and which may be applied at very low cost so as to avoid unduly increasing the cost of stoppers equipped with the improved pull.

Other objects and advantages of the invention will be understood by reference to the following specification and accompanying drawing (1 sheet) in which several selected embodiments of the invention are shown.

In the drawing:

Fig. 1 is an axial section through the mouth end of a bottle or similar container equipped with a stopper having a pull embodying one form of the invention.

Fig. 2 is a plan of the structure shown in Fig. 1, and

Figs. 3, 4, and 5 are side elevations of stoppers embodying various modifications of pulls according to the invention.

In Figs. 1 and 2 of the drawing, the mouth portion of a glass bottle or similar container is indicated at 1 and a stopper 2 of cork or similar material is shown seated in the mouth of the bottle. The inside of the mouth of the bottle

tapers slightly from its outer end toward the inside of the bottle in accordance with conventional practice, and stopper 2, being of cork or similar material, is under compression and conforms to the inside wall of the bottle mouth so as to frictionally hold the cork tightly in place in the bottle mouth.

As shown in Fig. 1, the outer end 3 of the stopper is flush with the outer end 4 of the bottle mouth so that, in the absence of the provision of a pull such as will presently be described, the stopper could be withdrawn only by the use of a corkscrew, or by means of some prying instrument, the use of either of which definitely tends to damage the stopper so as to impair its utility for reuse.

To facilitate withdrawal of the stopper 2, a pull 5 is provided, the pull consisting of a length of compressible, fibrous material, and preferably of a length of so-called chenile wire. Chenile wire usually comprises two small diameter wires twisted together with textile material such as short threads anchored between the wire in such manner as to form a textile covering for the twisted wires. This chenile wire is typified by common cleaners for the stems of tobacco pipes.

In the arrangement shown in Fig. 1, a length of chenile wire is folded upon itself so as to provide legs 6 and 7 disposed side-by-side. These legs 6 and 7 are inserted into the stopper 2 either manually or by means of machinery, and adhesively anchored to the stopper.

To facilitate insertion of the legs 6 and 7 of the pull, a suitable needle may first be inserted into the stopper to open up a passageway for the legs 6 and 7, after which the legs can be worked into the stopper. The legs may be preliminarily coated with suitable adhesive, or better, the passageway may be formed by means of a hollow needle, like a hypodermic needle, through which adhesive may be injected into the passageway as the needle is withdrawn, after which the legs of the pull may be worked into the adhesive-containing passageway.

By employing a longitudinally-grooved hollow needle, the needle and the legs of the pull may be simultaneously inserted, and the needle alone withdrawn, leaving the legs of the pull in place in the stopper. The desired adhesive may, of course, be injected through the hollow of the needle. By suitable means, a shot of adhesive may be introduced into the passageway formed by the needle as the needle is being inserted into the stopper, after the needle has been inserted

to its full depth and while it remains so inserted, or, if preferred, this adhesive application may be effected during withdrawal of the needle.

The adhesive, upon setting and drying, will effectively bond the textile-covered wires to the stopper so as to permit removal of the stopper through the agency of the pull and without withdrawing the pull from the stopper. The adhesive probably tends to improve the anchorage of the fibers of the pull to the wire thereof when chenile wire is employed, and the effectiveness of the anchorage of the pull to the stopper may be due, in part, to attachment of both ends of the multiplicity of fibers of the pull to the stopper.

It appears that the textile cover material on the twisted wires enables the cement or glue to effectively bond the pull to the stopper, whereas experiments have shown that plain wire cannot be effectively bonded to a cork by the application of cement in the manner above indicated. Any suitable cement or glue may be employed, many being commercially available.

As indicated in Fig. 1, the portion of the pull 5 which projects from the stopper may be opened into loop form to permit insertion of a finger through the loop for pulling purposes, or the pull may be otherwise shaped as desired. For initial packaging purposes, the pull 5 may be folded down into flat condition on the top of the stopper 3 as indicated in dotted lines at 8 in Fig. 2. As there indicated, the loop portion of the pull is closed on itself, and the closed loop folded down into flat position on the top of the stopper.

When pulling force is applied to the stopper through the agency of a pull such as described, it appears that the stopper is initially slightly deformed as represented in dotted lines 9 and 10 at the top and bottom ends respectively of the stopper. The indicated deformation of the stopper seems to have the effect of slightly contracting the diameter of the stopper so that there is an effect of loosening the stopper in the bottle mouth as a step preliminary to the actual withdrawal of the stopper from the bottle.

In Fig. 3 there is shown a modified form of pull in which a single strand 11 of chenile wire has one end portion introduced into the stopper and cemented in place as above described. The inner end of the pull may be refolded on itself as indicated at 12 and this refolded portion hooked over the end of a suitable needle to facilitate insertion of the pull in substantially the manner above described in respect of the construction shown in Figs. 1 and 2. The stopper 13, like the stopper 2 is preferably of cork material, although other compressible materials may be substituted. Cork is referred to inasmuch as such material is the most practical, and is conventionally used for stopper purposes.

In the modification shown in Fig. 4, a length of chenile wire is shown doubled upon itself to provide straight leg portions 14 and 15 and a small eye portion 16. The legs 14 and 15 are inserted in and bonded to the stopper 17 substantially as explained above in connection with the structure shown in Fig. 1. The provision of a small eye 16 is desirable for employment in connection with a rigid, hook-like instrument which may be engaged with the eye 16 for pulling the stopper. This small eye arrangement may advantageously be employed in connection with a suitable hook fastened securely to a wall or table or the like.

In Fig. 5 a length of pull material 18 is shown formed into inverted U-shaped form with its two legs 19 and 20 separately inserted and bonded to

the stopper 21. This arrangement is especially desirable in connection with larger stoppers, although it is not necessarily confined to that use.

In each of the described arrangements, a simple length of suitable flexible cordage of textile or other material may be substituted for the chenile wire. The employment of material of a fibrous nature, and its insertion into the stopper as illustrated, provides adequate and effective pull surface to which the adhesive may attach itself while also attaching itself to the material of the stopper so as to effectively bond the pull and stopper together.

The chenile wire material does not necessarily produce any stronger bond than cordage of equivalent outside diameter, but it offers some advantages in respect of handling of the pull material and its insertion into the stopper. Hence, such chenile wire is presently preferred for the indicated purpose, although it is not essential to the practice of the invention.

The described stopper pull arrangement facilitates the employment of smaller stoppers, in respect of both diameter and length, in many applications and thus brings about a saving in respect of the cost of stopper material employed which more or less offsets the cost of the pull material and its attachment to the stopper. In many cases, a shortened stopper may be employed so that when inserted in a bottle mouth, the outer end of the stopper is flush with the outer end of the bottle mouth. In addition to reducing the required amount of stopper material, this flush-end arrangement facilitates the application of additional sealing covers or coatings and reduces the overall length of the stoppered bottles so that smaller and hence less costly cartons or packing containers may be employed.

Various other advantages may be perceived, and other specific forms and applications of pulls may be used while employing the principles of the invention.

I claim:

1. A bottle stopper provided with a pull member, the stopper being a body of compressible material, and the pull member being a pair of wires twisted together with a filler of fibers squeezed between and projecting from opposite sides of said twisted wires along the length thereof, said fiber-bearing twisted wire being doubled on itself and the two free end portions thereof being inserted into said body from one end thereof to points short of the other end thereof, said inserted portions of said pull member being resiliently gripped by and adhesively bonded to the stopper, the portion of said fiber-bearing wire which projects from said stopper body being formable into a loop in which the fiber material provides a cushion whereby the loop may be comfortably engaged with a finger for the purpose of pulling the stopper out of the mouth of a bottle.

2. A bottle stopper provided with a pull member, the stopper being a body of compressible material, and the pull member being a pair of wires twisted together with a filler of fibers squeezed between and projecting from opposite sides of said twisted wires along the length thereof, said fiber-bearing twisted wire being doubled on itself and the two free end portions thereof being positioned side by side in contact with each other and inserted into said body from one end thereof to points short of the other end thereof, said inserted portions of said pull member being resiliently gripped by and adhesively bonded to the stopper, the portion of said fiber-bearing

wire which projects from said stopper body being formable into a loop in which the fiber material provides a cushion whereby the loop may be comfortably engaged with a finger for the purpose of pulling the stopper out of the mouth of a bottle.

JOHN OFTEDAHL.
